UNITED STATES PATENT OFFICE.

JAMES T. ATWOOD, OF ROCKFORD, ILLINOIS.

SASH OPERATOR.

Application filed June 21, 1923. Serial No. 646,772.

This invention relates in general to closure operators, and has more particular reference to those especially adapted for opening and closing casement windows.

The primary object of the present invention is to provide an improved means for opening and closing casement windows, so constructed as to be operable from the inner side of the sill and an interposed screen, if 5 such is used.

Another object is to provide an improved closure operator of this kind, comprising but few parts, which will serve in a practical way the purpose intended, and which 15 may be constructed and installed at a comparatively low cost.

In furtherance of the foregoing, I have provided an articulated rod slidable through a bore in the stool or interior sill of a window structure, connected at its outer end 20 to the sash and operable at its inner end for swinging the sash, and manually releasable means associated with the stool for locking the rod in any position to which it may be 25 adjusted. This provides a substantial connection for holding the sash and permits of quick adjustment for opening and closing the window sash.

Other objects and attendant advantages 30 will be appreciated as the invention becomes better understood by reference to the following description when considered in connection with the accompanying drawings,—

Figure 1 is a horizontal section through a 35 casement window structure embodying my invention;

Fig. 2 is an enlarged vertical section taken substantially on the line 2—2 of Fig. 1;

Figs. 3 and 4 are horizontal sections taken 40 on the line 3—3 and 4—4, respectively, of Fig. 2; and

Fig. 5 is a section taken on the line 5—5 of Fig. 3.

My invention is particularly designed for 45 application to casement windows; and in illustrating its application I have in the drawing shown briefly, a conventional casement window construction of the kind used for dwellings, including a screen at the inner side of the window sash. The principal parts making up the window frame are the stool or interior sill 6, uprights 7 and 8 and inner and outer facing strips 9 and 11. The window sash 12 is hinged on the frame at 50 13 and swings outwardly. In the present

instance, a screen 14 is positioned at the inner side of the casement window.

My invention contemplates the provision of an articulated rod slidable through the stool and connected to the sash for swinging the latter, and in the further provision of manually releasable means co-operating with the rod for locking it in any adjusted position, these parts being associated with the stool in a novel and advantageous manner as 60

will be presently apparent. The rod comprises inner and outer sections 15 and 16 respectively, articulated or pivotally connected together at 17 and slidable lengthwise through a bore 18 in the stool. This bore at 70

right angles to the face of the stool, is in the horizontal plane of the lower portion of the sash so that the outer end of the rod may be connected directly to the lower member 75 of the sash frame. As shown in Figs. 2 and 4, said outer end of the rod is pivotally connected at 19 to the sash, this connection being at present established through the agency

of a short rod section 21 set into the sash and secured thereto by means of a wood screw 22. By sliding the rod lengthwise in 80 its bore, it will be manifest that the sash will be swung on its hinge; and in order to provide clearance for the outer rod section 16

during the initial portion of the opening 85 movement, the stool is cut away in a horizontal plane at one side of the bore 18 as indicated by 23. When the joint 17 reaches an extended position, the outer rod section 16

will, of course swing entirely free from the 90 stool. A suitable knob 24 is provided on the inner end of the rod section 15 to facilitate sliding the rod back and forth. It will be observed that the joint 17 permits of the 95

desired relative horizontal movement between the rod sections 15 and 16 to accommodate opening and closing of the sash in the extended positions of the rod, and that when the sash is closed said joint is disposed beyond the inner side of the stool, thereby permitting the inner rod section to be swung to an inoperative position. In the present

instance, this inner rod section 15 will be 100 swung substantially parallel to the face of the stool and will be retained in this position by a spring clip 25. It will be further observed that in this position the articulated rod construction prevents opening of the

sash to any appreciable degree.

For the purpose of locking the window 110

sash in any position to which it may have been adjusted, I have provided a manually releasable device carried by the stool in a concealed position and adapted for releasably engaging the rod. This device comprises a plate 26 secured to the underside of the stool on its overhanging inner portion, and equipped with a pair of rod gripping elements 27. These elements, respectively fulcrumed at 28 on the plate, embrace the rod and are adapted to be urged into gripping contact with said rod by the action of concealed expansion springs 29 supported on the rod. By pressing the pending ends 31 of said gripping elements together against the pressure of the springs 29, said elements may be released from the rod, permitting the same to be freely adjusted. At present, the plate 26 has formed therewith, an upstanding annular flange 32 fitted into the stool and against which the outer ends of the springs bear. This gripping device may be easily set into the stool by boring the latter from the under side as at 33, this bore intersecting the bore 18, as is plainly shown. It will be obvious that by pressing together the depending ends 31 of the gripping elements, the rod will be released so that it may be slid freely back and forth for opening and closing the window sash, and that upon releasing said elements they will be instantly and automatically brought into gripping engagement with the rod by the action of the springs for locking the rod in any position to which it has been adjusted.

From the foregoing it will be noted that the rod comprises only an outer and an inner section pivotally connected together at 17 and that this rod is so mounted and guided that its pivotal connection 17 follows the axial plane of the bore 18 at all times and is disposed at the outer edge of the stool when the sash is full open and beyond the inner edge of the stool when the sash is closed, and that at all times the rod is so guided as to maintain this position of said pivotal connection whereby to hold the sash in any position to which it may be set by lengthwise adjustment of the rod in the stool and when locked in such position by means of the locking device. In the present embodiment of my invention the rod is thus guided by contact with the stool which it will be observed is shaped to pro-

vide lateral support for the inner rod section 15 at any and all lengthwise adjusted positions thereof in the bore, and that said bore is elongated horizontally at its outer end and through a portion of its length to provide clearance for the outer rod section 16 when the latter swings horizontally before leaving the bore. This provides a sash operating means of the fewest possible elements which serves in a very practical and effective manner for holding the sash either closed or opened or in any intermediate position.

It is believed that the foregoing conveys a clear understanding of the objects prefigured above, it being noted however, that the particular construction disclosed herein is for illustrative purpose merely, and that changes might be made in the construction and arrangement of parts without departing from the spirit and scope of the invention as expressed in the appended claim.

I claim:

In combination with a window frame and a casement window sash hinged therein for swinging movement in opening and closing, the window frame having a sill which overhangs an inside wall at its inner edge, of a sash-operating rod comprising an inner and an outer section hinged together, the outer section extending through a hole drilled through said sill from its inner edge to the outer edge whereby to be concealed from view and to leave the top of the sill clear, said outer section having pivotal connection with said sash at its one end and projecting slightly beyond the inner edge of said sill at its opposite end, the inner section being adapted to lie along the inner edge of said sill in an out-of-the-way inoperative position but arranged when swung into alignment with said outer section to be extended through the aforementioned hole in said sill to operate said sash, and a finger-operated holding device for releasably securing said rod to hold said sash in any desired position of adjustment, said device being received in an opening made in the under side of said sill at its overhanging inner edge and extending from beneath the overhanging edge whereby to be concealed from view while conveniently accessible for operation during the operation of said rod.

JAMES T. ATWOOD.
